UNITED STATES PATENT OFFICE.

ELMER R. PARSONS, OF OMAHA, NEBRASKA.

PANEL-OPERATOR FOR PLAYER-PIANOS.

1,168,109.

Specification of Letters Patent. Patented Jan. 11, 1916.

Application filed July 15, 1915. Serial No. 40,048.

To all whom it may concern:

Be it known that I, ELMER R. PARSONS, a citizen of the United States, residing at Omaha, in the county of Douglas and State of Nebraska, have invented certain new and useful Improvements in Panel-Operators for Player-Pianos; and I do hereby declare the following to be a full, clear, and exact description of the invention, such as will enable others skilled in the art to which it appertains to make and use the same.

This invention relates to improvements in player-pianos and especially with reference to means to operate the panels of a player-piano, the object of the invention being to provide improved devices of this character which are simple in construction, may be readily installed and by means of which the player-piano panels may be readily opened and closed.

The invention consists in the construction, combination and arrangement of devices hereinafter described and claimed.

In the accompanying drawings:—Figure 1 is a front elevation of the upper portion of a player-piano provided with sliding doors or panels and showing the lever for actuating the panel operating mechanism. Fig. 2 is a rear elevation of the doors or panels and the panel operating mechanism. Fig. 3 is a vertical sectional view on the plane indicated by the line *a—a* of Fig. 2. Fig. 4 is a detail perspective view of one of the attaching devices, and Fig. 5 is a detail view in side elevation of the segment gears, the radial arm, the lever and the link connecting the arm and lever, the shaft upon which the gears are mounted being in vertical section.

The front wall of a player-piano is indicated at 1, provided with the usual openings 2 for the music roll doors or panels 3—4. These panels are provided on their lower sides with supporting rollers 5 which operate on a lower track and guide bar 6, an upper guide bar 7 being also provided which is engaged by the upper sides of the panels. A vertically arranged bar 8 is secured to the inner side of the front wall 1 in spaced relation thereto, and in rear of the guides 6—7 and is arranged near one end of the opening 2. An operating shaft 9 is mounted in a bearing 10 in the wall 1 and also in a bearing 11 near the upper end of the bar 8. An operating lever 12 is attached to the front end of said shaft and a segment gear 13 is attached to said shaft at a point near its

rear end. A segment gear 14 engages the segment gear 13 and its shaft or axle 15 has a bearing in the bar 8 and also in a brace 16 on the inner side or rear side of said bar. Said segment 14 has a radial arm 17.

The panel or door 3 has a block 18 on its inner side near its outer end, a link 19 being pivotally connected as at 20 to said block. A lever 21 is pivotally connected to the link 19 as at 22 and its upper end is pivotally connected to the upper guide 7 as at 23. A link 24 connects the lever 21 with the arm 17.

When the shaft 9 with the segment 13 is turned by the lever 12 in one direction, the segment 14 is also turned, together with its arm 17, said arm coacting with the link 24, lever 21 and link 19, to move the panel 3 to open or closed position according to the direction in which said lever 12 is turned, as will be understood.

The panel 3 is provided near its upper outer corner with an attaching device 25 by means of a screw 26. The panel 4 is provided near the corresponding corner with an attaching device 27. A pulley 28 is mounted on the guide 7 above the panel 3 and near one end of the panel opening, a similar pulley 29 being mounted on said bar near the opposite end of the panel opening and above the panel 4. An operating cable 30 has one end attached to one end of the attaching device 25, passes over the pulley 28 and has the opposite end attached to one end of the attaching device 27. A similar cable 31 has one end attached to the other end of the attaching device 25, passes over the pulley 29 and has the other end attached to the other end of the attaching device 27, said cables being crossed as will be understood.

As shown in Fig. 4 of the drawings, each of the attaching devices 25 and 27 comprises a hub 25^a and arms 25^b, the arms extending laterally from opposite sides of the hub. The hubs 25^a are provided with openings 25^c to permit the attaching devices to be pivotally secured to the panels 3 and 4 by the element 26, and the arms 25^b are provided with openings 25^d to permit the cables 30 and 31 to be connected thereto.

The cables and the pulleys form connections between the panels which cause the panel 4 to be operated simultaneously with the panel 3 and in the reverse direction, so that said panels are simultaneously opened or closed.

While I have herein shown and described a preferred form of my invention I would have it understood that changes may be made in the form, proportion and construction of the several parts without departing from the spirit of the invention and within the scope of the appended claims.

Having thus described my invention, I claim:—

- 10 1. In a player-piano a slidably mounted panel, a shaft having an operating lever and also provided with a gear, a second gear engaged with the first gear, suitably mounted for oscillating movement and provided with an arm rigid therewith, a link pivotally connected to the panel, a lever having one end pivotally mounted at a fixed point and the other end pivotally connected to said link and a second link connecting said lever to the arm.
- 15 2. In a player-piano, a pair of slidably

mounted panels, manually operable means by which one of said panels may be opened and closed, said means comprising a shaft having an operating lever and also provided with a gear, a second gear engaged with the first gear, said second gear being mounted for oscillating movement and provided with an arm rigid therewith, a link pivotally connected to one of said panels, a lever having one end pivotally mounted at a fixed point and the other end pivotally connected to said link, and a second link connecting said lever to the arm, and means operable by said panel to simultaneously open and close the other panel.

In testimony whereof I affix my signature in presence of two witnesses.

ELMER R. PARSONS.
